UNITED STATES PATENT OFFICE.

WILLIAM H. WOOD, OF ROCHESTER, NEW YORK.

SHOE.

SPECIFICATION forming part of Letters Patent No. 228,155, dated May 25, 1880.

Application filed August 28, 1879.

To all whom it may concern:

Be it known that I, WILLIAM H. WOOD, of the city of Rochester, county of Monroe, and State of New York, have invented a certain 5 new and useful Improvement in Shoes; and I do hereby declare that the following is a full, clear, and exact description of the same, reference being had to the accompanying drawings, which show my improvement applied to 10 the fly or button-flap of the shoe.

My improvement relates to the button-holes of shoes and the process of making them, by which a beaded or turned-over lining to the button-hole is produced, which insures great 15 strength and long wear, all as hereinafter described.

The figures in the drawings show the several steps in the process of making the button-hole in my improved manner, and which I will 20 now proceed to describe.

A, Figure 1, represents the outer layer or thickness of leather of the button-hole fly or flap. In this layer are cut, at proper distances apart, a series of slits, *a a*, for the button-holes.

B B, Fig. 2, are a series of pads of thin leather, which are placed over the thickness A, and covering the slits *a a*. These pads are stitched to the leather around and close to 30 the edges of the slits, as shown at *b*, (at the left in Fig. 2,) and when this is done the pads themselves are slitted, as shown at the right in Fig. 2, so as to come in line with the button-holes. The loose edges of the pads B B are then bent inward and carried through the 35 slits, so as to lie on the under side of the leather, as shown in Fig. 3, leaving thereby a bead or lining all around the margin of the button-hole, and covering up and shielding the raw edge of the leather. To facilitate the 40 turning of the pads, the same are preferably notched or slitted at top and bottom before turning, as shown at *c c*, Fig. 2; but this may be dispensed with and the pad be left whole.

The finishing step of the process consists in 45 placing the lower thickness or layer of leather, D, over the upper one, A, with the loose edges of the pads B B resting between them, and then producing a line of stitching, *d*, around 50 the button-hole, said stitching passing through the two thicknesses of leather and the pads,

and securing them fast in place, as shown in Fig. 4.

By the means above described a beading or lining having a turned edge, covering the raw 55 edge of the upper thickness of leather, is produced, which will stand great strain and wear, and will endure as long as the shoe will.

I am aware that a stamped lining shaped to the button-hole and resting between the 60 two thicknesses of leather is well known; but in such case the edges of the upper layer are left exposed and raw, and a single line of stitching only holds the parts in place.

In my invention the pad is turned inward 65 and over the edge of the upper thickness, covering and shielding the same, and it is protected by two separate and distinct lines of stitching, the first of which secures the edge of the pad to the edge of the leather, where 70 the greatest strain comes, and the last of which secures all the thicknesses together outside the button-hole.

I design to apply this invention to cloth as 75 well as leather shoes, the layers and pads all being made of cloth, or a part of cloth and a part of leather.

I design also to use it in the key-hole or 80 eyed button-holes, as shown in Fig. 5, as well as in straight ones.

The lower layer, D, is the same known as the "button-fly" lining in ordinary shoes. The pads also form stays to support the layers around the button-hole.

Having thus described my invention, what 85 I claim as new is—

1. The method or process herein described of forming button-holes in shoes, which consists in first slitting the upper layer, then placing pads over said slits, stitching said pads 90 to the edges of the slits, and cutting through said pads in the line of the slits, then turning the outer edges of the pads inward, inserting them through the slits and turning them outward on the under side, and finally 95 placing the lower layer over the upper one, covering the pads, slitting said lower layer in line with the button-holes, and stitching through the two layers and the pads outside the button-hole, as herein shown and described. 100

2. A boot or shoe in which the button-holes are protected by slitted pads, which are first

sewed on the right side of the material composing the upper, and then turned through the slits forming the button-holes, so as to cover or line their edges, and secured by lines of stitching on the under side, substantially as specified.

In witness whereof I have hereunto signed

my name in the presence of two subscribing witnesses.

WILLIAM H. WOOD.
